UNITED STATES PATENT OFFICE.

SAMUEL B. GOLD, OF INDEPENDENCE, MISSOURI, ASSIGNEE TO WEBER ENGINE COMPANY, OF KANSAS CITY, MISSOURI, A CORPORATION OF IOWA.

SPRAYING NOZZLE FOR OIL ENGINES.

Application filed March 28, 1921. Serial No. 458,321.

To all whom it may concern:

Be it known that I, SAMUEL B. GOLD, citizen of the United States, and resident of Independence, county of Jackson, State of Missouri, have invented a certain new and useful Improvement in Spraying Nozzles for Oil Engines, of which the following is a complete specification.

This invention relates to spraying nozzles for oil engines, and has for its primary object to produce a nozzle in which the possibility of interruption in the flow of the oil from clogging of the nozzle, is practically eliminated. A nozzle of this character is 10 very desirable, as in all engines with which I am familiar, operated with crude oil, especially where such oil comes direct from the wells, shut-downs due to clogging of the oil nozzles, are of frequent occurrence. These 15 shut-downs are expensive, and they involve loss of production as well as loss of time, and it sometimes happens that the clogging of a nozzle results in the rupture of the supply piping, and sometimes, in injury, more or less 20 serious, to the engine.

Another object of the invention is to produce a nozzle which is leak-proof, to guard against charging the combustion chamber of the engine with oil, when the engine is at 25 rest, or before the required pumping pressure is developed.

A still further object is to produce a nozzle which is self-cleaning at the tip, and which is of knock-down construction to facilitate cleaning at intermediate points in its 30 length.

With the objects mentioned in view, the invention consists in certain novel and useful features of construction and combinations of 35 parts, as hereinafter described and claimed; and in order that it may be fully understood reference is to be had to the accompanying drawing, in which:—

Figure 1 is a side elevation of an oil engine 40 nozzle embodying the invention.

Figure 2 is a central longitudinal section of the nozzle.

Figure 3 is a cross-section on the line III—III of Figure 2.

Figure 4 is a cross-section on the line 45 IV—IV of Figure 2.

Figure 5 is an end view of the nozzle.

In the said drawing, a plug comprises an angular head 1 and a threaded portion 2 for engagement with a threaded opening in the

wall of an engine, (not shown), to form a support for the nozzle 3. The plug is smooth internally and is formed with a forwardly-facing shoulder 4 for engagement by a rearwardly-facing shoulder 5 formed on the nozzle, and the latter is provided at its rear end with a reduced threaded portion 6 engaged by a clamping nut 7, which bears against the rear face of the nut 1 for the purpose of clamping the shoulder of the nozzle firmly 60 against the shoulder of the nut and thus holding the nozzle in rigid relation to the nut 1.

A nut 8 engages the rear end of the portion 6 of the nozzle, and also fits over the 70 flanged front end of a nipple 9, screwed upon the front end of the oil supply pipe 10 of the nozzle, said nut 8 and nipple 9 constituting a union for securely connecting the nozzle with the oil supply pipe. The tip of 75 the nipple 9 is of conical form as at 11 and is centered in a conical mouth 12 formed in the rear end of the portion 6 of the nozzle, as shown clearly in Figure 2.

The nozzle in its preferred form, comprises the rear portion engaged by the nut 1 80 and intermediate portion 13, and a tip portion 14, the front end of the rear portion being internally enlarged and threaded as at 15 and engaged by the externally-threaded reduced 85 rear end 16 of the intermediate portion 13. The front end of the intermediate portion 13 is internally-threaded as at 17, and is engaged by the reduced externally-threaded rear portion 18 of the tip portion 14. By 90 this arrangement it is obvious that the sections of the nozzle can be readily secured together or separated.

The portion 6 of the rear member of the 95 nozzle is provided with a central bore 19 reduced slightly at its rear end to provide a valve seat 20, engaged by a ball valve 21, and said valve is held upon its seat by a spring 22, fitting around the reduced stem of a threaded plug 23 against which the front 100 end of said spring bears. Said plug is preferably threaded and screwed into the portion 6, and to provide for the passage of oil, the said plug is preferably flattened as at 24. It will thus be seen that the ball valve 20 is 105 held upon its seat with a yielding pressure, so that when the pressure upon its opposite side or face, developed by the operation of the customary pump (not shown) used in connection with engines of this type, exceeds 110

- the pressure of said spring, the valve will open and permit oil to pass, said valve however remaining closed normally so that oil cannot leak past it.
- 5 The rear portion of the nozzle at the point of communication between the bore of portion 6 and the enlargement of said bore, provides a valve seat for a ball valve 25, and engaging said valve is a pin 26, 10 surrounded by a spring 27, which bears at one end against the pin and at the other end against the section 13, for the purpose of holding valve 25 upon its seat until a preponderating pressure is applied upon the 15 said valve by the oil. It will thus be seen that this valve 25 affords a second check against the leakage of oil forwardly through the nozzle, and in practice the resistance of spring 27 will exceed that offered by the 20 spring 22, but will of course yield when the pump heretofore mentioned, has developed the required pressure.
- The tip section or member 14 of the valve is provided at its tip end with a flaring 25 opening 28, provided with an exit groove 29 through which the oil is adapted to be sprayed under the pressure from the pump. A conical valve 30 normally closes the tip opening except the exit passage 29 thereof, 30 and said valve 30 is provided with a stem 31 diametrically reduced at its front end at 32 to provide a chamber for holding sufficient oil to guard against irregular or spasmodic spraying action. At its rear end 35 the stem is reduced as at 33, and between portions 32 and 33, is provided with longitudinal grooves or passages 34 to accommodate the flow of oil from section 13 to the tip of the nozzle. One or more nuts 35 40 are secured upon the rear of portion 33 of the valve stem, and a spring 36 surrounds said stem and bears at its front end against portion 14 of the nozzle, and at its rear end against one of said nuts 35, and thus normally holds the valve upon its seat, said 45 spring being adapted to yield to permit the valve to be unseated by the pressure of oil, only in the event that the orifice 29 becomes clogged to the ejection of oil. In the event 50 such clogging occurs and the pressure of oil becomes undesirably high, the spring 36 will yield, the valve being reseated by said spring as soon as the pressure falls sufficiently. Under normal condition the opening 55 of the valve will result in the unclogging of the exit passage 29, but should this not occur, the valve will continue to periodically open and thus guard against any back pressure which might rupture the 60 supply pipe 10 or result in injury to the pumping mechanism or any part of the engine, it being understood that the snapping of the valve back upon its seat has a tendency to dislodge clogging matter from the orifice 65 29, and thus minimize opening movements
- of valve 28, and such irregularity or spasmodic discharge of oil as is incidental to opening and closing movements of said valve. When the attendant notes any sustained irregularity in the operation of the 70 engine, the nozzle can be readily detached and cleaned and quickly restored to normal condition, or the operator can manually manipulate the pump to impart quick opening and closing movements to the valve 30 75 for the purpose of discharging clogging matter from said passage as well as from the valve itself.
- From the above description, it will be apparent that I have produced a nozzle for 80 oil engines, which embodies the features of advantage set forth in the statement of the objects of the invention, and which obviously may be modified in various particulars without departing from the principle 85 of construction and mode of operation involved.
- I claim:
1. An injector for oil engines, comprising a body portion having a discharge end provided with a discharge opening of large area and a supplemental discharge opening of small area, a longitudinally extending valve stem within said body whose inner end is subjected to the pressure within the injector, said valve stem having at its outer end a conical head normally closing the larger opening while leaving the smaller opening unobstructed and having a reduced portion within the body forming a chamber, 90 a spring surrounding the valve stem within said body and exerting a pressure thereon sufficient to close the valve when the pressure is normal within the injector, but permitting the valve to open when the smaller opening is obstructed.
  2. An injector for oil engines, comprising a body portion having a discharge end provided with a discharge opening of large area and a supplemental discharge opening of small area, a longitudinally extending valve stem within said body whose inner end is subjected to the pressure within the injector, said valve stem having at its outer end a conical head normally closing the larger opening while leaving the smaller opening unobstructed and having a reduced portion within the body forming a chamber adjacent the conical head, a spring surrounding the valve stem within the body, 100 an adjustable member on the stem against which one end of the spring bears, whereby the tension of the spring may be set to hold the valve closed under normal pressure within the injector but permit it to open when the smaller opening is obstructed.
- In witness whereof I hereunto affix my signature.

SAMUEL B. GOLD.
